US00D702237S

(12) **United States Design Patent**
Oberpriller et al.

(10) **Patent No.:** US D702,237 S
(45) **Date of Patent:** ** Apr. 8, 2014

(54) **IMAGING TERMINAL**

(71) Applicant: **Hand Held Products, Inc.**, Fort Mill, SC (US)

(72) Inventors: **Mark L. Oberpriller**, Atlanta, GA (US); **Timothy R. Fitch**, Syracuse, NY (US); **Donna M. Fletcher**, Auburn, NY (US)

(73) Assignee: **Hand Held Products, Inc.**, Fort Mill, SC (US)

(**) Term: **14 Years**

(21) Appl. No.: **29/446,944**

(22) Filed: **Feb. 28, 2013**
